UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

GUARD FOR STARTING MECHANISM OF SEWING-MACHINES.

1,398,523.

Specification of Letters Patent. Patented Nov. 29, 1921.

Application filed April 26, 1920. Serial No. 376,500.

To all whom it may concern:

Be it known that I, JOHN KIEWICZ, a citizen of the United States, residing at Boston, county of Suffolk, State of Massachusetts, have invented an Improvement in Guards for Starting Mechanism of Sewing-Machines, of which the following description, in connection with the accompanying drawing, is a specification, like characters 10 on the drawing representing like parts.

This invention relates to sewing machines and particularly to sewing machines of that type which are provided with a work-holding means that is removable from the frame 15 and replaceable therein, and one of the principal objects of the invention is to provide a safety guard which will prevent the operator from starting the machine if the work-holding means is not in its proper position. If the sewing machine should be started with the work-holding means in an 20 improper position, there is danger that some of the moving parts would be broken or damaged.

While my invention is applicable to different sewing machines, I have shown it herein as it would be applied to a buttonhole sewing machine of the type shown in United States Patent No. 1,188,942, June 27, 1916.

In this patent the work-holding means which holds the work in which the buttonhole is to be formed comprises a clamp-plate slidably mounted in ways in the bed-frame of the machine and removable bodily from said ways, and work-clamps pivotally carried by the clamp-plate and removable bodily therewith. The device shown in said patent also comprises a starting lever arranged to be depressed by the finger of the operator and

which functions to set the machine in operation. In order that the machine may work properly, it is essential that before the starting lever is depressed to start the machine, the clamp-plate with the work-clamp pivoted thereto should be properly positioned in the ways and properly connected to the feed mechanism by which the clamp-plate is given its feeding movement, for otherwise some of the parts of the machine are liable 45 to be damaged. I have, therefore, in the present invention provided a guard member which is constructed to prevent the starting lever from being depressed except when the clamp-plate is properly positioned in

its ways and connected to the mechanism 55 which gives it the feeding movement.

Since the invention relates simply to the means for preventing the operation of the starting lever except when the work-clamp is properly positioned, I have not deemed 60 it necessary to illustrate a complete sewing machine herein, but have simply shown a sufficient portion thereof to enable my invention to be understood.

Figure 1 is a plan view partly broken away 65 of the clamp-plate, starting-lever and portion of the bed-frame of a sewing machine embodying my invention.

Fig. 2 is a side view of the starting-lever and safety-guard looking from the top of 70 Fig. 1.

In the drawings, 1 indicates the bed-frame of a sewing machine of the type illustrated in the above-mentioned Patent No. 1,188,942, and 2 is the clamp-plate portion 75 of the work-holding means which slides back and forth in suitable ways 3 formed in the bed-plate. The clamp-plate has pivoted thereto the usual work-clamps 4, said clamps being sustained by the pivoted arms 5. The 80 starting lever by which the machine is started is mounted on the bed frame and is indicated at 6, and it is shown as carried by a vertical stud 7 which is capable of rocking about a horizontal axis, and is formed at its 85 end with a finger piece 8 to receive the finger of the operator. The machine is started by depressing this lever toward the bed-plate, this movement rocking the stud 7 and thereby releasing the clutch mechanism which starts the machine, all as shown in the above-mentioned patent.

To prevent the starting lever from being actuated except when the clamp-plate 2 is properly positioned, I have provided a 95 guard member 9 in the form of an L-shaped plate which is situated between the starting-lever and the bed-plate 1 and is pivotally connected to the bed-plate at 10. The starting-lever is formed with a depending projection 11 and the bed-plate is also formed with an opening or recess 12 to receive said projection when the starting lever is depressed. The safety guard 9 is also formed with an opening 13 which when alined with the opening 12 permits the starting lever to be depressed. If, however, this opening 13 is out of line with the recess 12, then the

starting lever is prevented from being depressed by engagement of the projection 11 with the guard member 9. Therefore, in order to start the machine, it is necessary 5 that the guard-plate should be properly positioned.

The safety-guard is so constructed that when the clamp-plate 2 is properly positioned in the machine, said safety-guard will 10 be held thereby in a position with its aperture 13 in alinement with the recess 12, but when the clamp-plate is removed from the machine or has not been properly inserted, said guard member will be held in a position 15 wherein the aperture 13 is out of line with the recess 12. While this result may be accomplished in various ways, I have herein shown a construction wherein the safety-guard 9 is acted on by a pulling spring 14 20 which tends normally to swing it into a position with the aperture 13 out of line with the recess 12. This pulling spring is connected at one end to the guard-member 9 and at the other end to a post 15 which is rigid with 25 the bed-plate 1 and is located in a notch 16 formed in the safety-guard. The end 17 of the notch acts as a stop to limit the spring-impelled swinging movement of the guard-member. The safety guard member is also 30 formed with an extension or cam portion 18 which is situated to be engaged by the portion 19 of the clamp-plate 2 when the latter after having been introduced into the ways 3 is moved toward the right, Fig. 1, 35 into the proper position to be connected to the feed mechanism. Such position is shown in Fig. 1. This connection with the feed mechanism is effected by a hook 20 on the clamp-plate engaging a pivoted latch 21 40 carried by the feed slide, all as shown in the above-mentioned patent.

The engagement of the parts 19 of the clamp-plate with the extension 18 of the guard member 9 will swing said guard member from the dotted to the full line position 45 Fig. 1 against the action of the spring 14, and when the guard-member is brought into the full line position the aperture 13 therein is carried into line with the recess 12 so 50 that the starting lever 6 can be depressed. The construction is such that the guard member 9 is not properly positioned to permit the starting lever to be depressed until 55 the clamp-plate has been moved into the position to be engaged with the latch 21 and, therefore, if the operator should insert the clamp-plate 2 carelessly and should not give it a sufficient movement to the right, Fig. 1, to engage it with the latch, the guard member 9 would not be positioned correctly to 60 permit the starting lever to be depressed, and, therefore, the operator would be unable to start the machine. When the clamp-plate 2 is disengaged from the latch 21 and re- 65 moved from the machine the spring 14 will

automatically swing the clamp plate 2 into its dotted line position, in which position it will prevent the actuation of the starting lever 6.

The guard member 9 is shown as having 70 a portion 22 which extends beyond the bed-plate 1 and which forms a finger piece that may be grasped by the operator to manually operate the guard member if it is desired for any purpose to start the machine when the 75 clamp plate is removed.

It will be seen from the above that with my invention if the operator has been careless in placing the clamp-plate in the machine and has not properly connected it to 80 the latch 21, the guard member 9 will prevent his depressing the starting lever and thus setting the machine in operation, and, therefore, if the operator attempts to start the machine and finds he cannot depress the 85 starting lever, he will know that the clamp plate is not properly positioned and will have to remedy the difficulty before he can start the machine.

I claim:

1. In a sewing machine, the combination with a base-frame, of work-holding means removable therefrom, a starting lever mounted on the base frame and by which the machine is started, and means to prevent the operation of the starting lever to start the machine until the work-holding means is in proper position.

2. In a sewing machine, the combination with a base-frame, of work-holding means removable therefrom, a starting lever mounted on the base frame and by which the machine is started, and means controlled by the work-holding means to prevent operation of the starting lever until the work-holding means is in proper position.

3. In a sewing machine, the combination with a base-frame, of work-holding means slidably mounted thereon and provided with a hook, of a latch member to engage said hook when the work-holding means is properly positioned, a starting lever mounted on the base frame and by which the machine is started, and means controlled by the work-holding means to prevent the starting lever from being operated except when said work-holding means is properly engaged with said latch.

4. In a sewing machine, the combination with a base-frame, of a clamp plate slidably mounted thereon, means to clamp the work to the clamp plate, a starting lever by which the machine is started, a guard member normally preventing operation of the starting lever, but adapted to be moved into a position to permit said lever to be operated by the clamp plate when the latter is in proper position.

5. In a sewing machine, the combination with a base frame, of work-holding means

- slidably mounted thereon, a latch to engage said work-holding means when in proper position, a starting lever by which the machine is started, a guard member normally preventing the operation of the starting lever, said guard member having a portion to be engaged by the work-holding means when the latter is in position to engage the latch whereby said work-holding means 5 when in such position holds the guard member in a position to permit the starting lever to be actuated.
6. In a sewing machine, the combination with a base frame, of work-holding means removable therefrom, a depressible starting lever mounted on the base frame and constructed to start the machine when it is depressed and means to prevent the starting lever from being depressed until the work- 10 holding means is in proper position.
7. In a sewing machine, the combination with a base frame, of work-holding means removable therefrom, a starting lever mounted on the base frame and by which the machine is started, and a movable guard mem- 15 ber which in one position is operative to prevent the starting lever from being operated and in another position permits said lever to be operated, said guard member being constructed to be moved into its inoperative position by the work-holding means when the latter are in proper position. 20
8. In a sewing machine, the combination with a base frame, of work-holding means removable therefrom, a depressible starting lever mounted on the base frame and provided with a finger piece by which it may be depressed thereby to start the machine, and a device movable from operative position in which it prevents the starting lever 25 from being operated to inoperative position in which it permits said starting lever to be operated, said device being moved into inoperative position by the work-holding means when the latter are in operative po- 30 sition. 35

In testimony whereof, I have signed my name to this specification.

JOHN KIEWICZ.
